(57) **CLAIM**

The ornamental design for a bottle opener, as shown and described.

DESCRIPTION

FIG. 1 is a right-side view of a bottle opener showing my new design;

FIG. 2 is a front view of the bottle opener.

FIG. 3 is a back view of the bottle opener.

FIG. 4 is a left-side view of the bottle opener.

FIG. 5 is a right-side view of the bottle opener.

FIG. 6 is a bottom view of the bottle opener.

FIG. 7 is a top view of the bottle opener.

FIG. 8 is a perspective view of the bottle opener.

FIG. 9 is a right-side view of a second embodiment of the bottle opener;

FIG. 10 is a front view of the bottle opener;

FIG. 11 is a back view of the bottle opener;

FIG. 12 is a left-side view of the bottle opener;

FIG. 13 is a right-side view of the bottle opener;

FIG. 14 is a bottom view of the bottle opener;

FIG. 15 is a top view of the bottle opener; and,

FIG. 16 is a perspective view of the bottle opener.

The broken lines showing a bottle in FIG. 1 and a refrigerator in FIG. 9 are included for the purpose of showing features in the environment that form no part of the claimed design.

1 Claim, 8 Drawing Sheets
